(57) **CLAIM**

The ornamental design for a garden lamp, as shown and described.

DESCRIPTION

FIG. 1 is a right front top perspective view of our new design for a garden lamp;

FIG. 2 is a left rear bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled portion of FIG. 1; and,

FIG. 10 is an enlarged detail view of the encircled portion of FIG. 2.

The broken lines shown in the drawings represent portions of the garden lamp that form no part of the claimed design.
